UNITED STATES PATENT OFFICE.

RANSFORD O. CANEDY AND JAMES M. CANEDY, OF NORTH ADAMS, MASSACHUSETTS.

ELECTRICAL FEELER FOR LOOMS.

Application filed October 18, 1926. Serial No. 142,340.

- This invention relates to an improved attachment for looms and it has reference to a device of this class which is commonly known in the art as a feeler, the same having more specific reference to a structure of this kind which is associated with the bobbin and shuttle for automatically stopping the loom before the filling has been exhausted in order to prevent mispicks.
- 10 Briefly, the invention has reference to a structure of this kind which is of an electrical nature and includes a base plate to be attached to a stationary part of the loom, there being a longitudinally movable spring 15 pressed feeler mounted upon this base and provided with a corrugated tip for cooperation with the filling on the bobbin. A feeler of this type has now become well known as the "side swipe" embodiment.
- 20 Our principal aim is to generally improve upon structures of this class by providing one of comparative simplicity and durability wherein the parts are associated in a novel manner to produce a more practical and efficient device, and one which will accurately detect the condition of the filling at all times and will positively come into play for stopping the loom before the filling is exhausted.
- 25 Other features and advantages of the invention will become apparent from the following description and drawings.
- In the drawings:—
- Figure 1 is a top plan view of the attachment per se, showing the parts in one position.
- 30 Figure 2 is a view like Figure 1, showing the parts in another position.
- Figure 3 is a cross section taken approximately upon the plane of the line 3—3 of Figure 1.
- 40 Figure 4 is a similar cross section showing the latch mechanism, and
- Figure 5 is a perspective view of the tip.
- 45 Referring to the drawings in detail it will be seen that the reference character 1 designates the base plate which is of general oblong configuration, the same being provided on one longitudinal edge with an elongated slot 2, serving to permit the device to be attached to the stock parts of the existing loom without requiring alterations. On the opposite side, the plate is formed with a peculiarly shaped guide slot 3, which serves in a manner to be later discussed.
- 50 At one end of the plate is a guide loop 4 through which the reduced end of the feeler
- 55 arm 5 slides. It will be noted however that the guide is somewhat elongated to permit the aforesaid "side swipe" action. The central portion of the arm is widened somewhat as at 6 and provided with a beveled shoulder. A pivoted latch 7 having an angularly directed detent or finger is seen plainly in Figure 4. Normally, this finger rests slidably upon the wide portion of the feeler. While 60 considering this part attention is directed to a bracket 8 which is mounted on the base plate and constitutes pivotal mounting for the latch, there being an upstanding lug 9 here, and a coil spring 10 being interposed between the lug and the butt end of the latch. This holds the detent of the latch in contact with the feeler in an obvious manner. It will be noted that the bracket includes an 65 elongated base 11 which is adjustably mounted on the main base plate 1. This permits accurate adjustment of the parts to render them more sensitive.
- 70 Fastened to the opposite end of the base plate is an arched part 12 constituting a 75 mounting for a pivot joint 13, the joint being formed with a central bore. The feeler is provided adjacent these parts with a reduced cylindrical extension 14 which extends slidably through the bore, and it will be 80 noted that a coil spring 15 surrounds this portion 14, and bears against the enlarged central body portion. It is plain to be seen that this spring serves to hold the corrugated tip 16 in contact with the filling on 85 the bobbin.
- 85 Attention is now directed to an upstanding ear 17 carrying an adjustable contact screw 18 with which a suitable electrical connection 19 is associated. Also, a bridge 90 piece 20 is carried by the central portion of the feeler and constitutes a relatively movable electrical contact for cooperation with the adjacent end of the contact screw 18. Furthermore, the feeler arm is provided on 95 its under side and at its center with a stud which is movable in the slot 3 and is adapted to engage one end of the same to limit the movement of the arm in one direction.
- 100 The operation of the device is quite like the ordinary feeler of the "side swipe" type, the distinction being that the present device is electrical and when it is moved over by the longitudinal motion of the bobbin, the contacts 20 and 18 come into play to close or 105 rather ground an electrical circuit for stopping the loom. The latch plays an impor-

tant part. Normally as the feeler arm reciprocates back and forth, resisted and affected by the action of the coil spring, the depending detent on the latch simply slides 5 or rides on the relatively wide central portion of the arm. However, after the material on the bobbin has substantially run out and the tip comes into engagement with the core of the bobbin and side swipe action 10 takes place the arm moves over, bringing the cross piece 20 into electrical engagement with the adjustable screw 18, thus stopping the machine. At this time, the detent on the latch 15 7 engages the lower central portion of the longitudinal edge of the feeler arm and holds the arm over, with the contacts thus engaged.

Of course when the new bobbin is placed 20 in the shuttle, the thickness of the material wrapped thereon forces the feeler arm down against the tension of the spring 15 and in so doing, the bevelled shoulder on the widened portion of the arm rides underneath the detent and lifts the latch up. The adjustability of the latch is desirable in that 25 different textures of material are used on the bobbin. Obviously, where silk is employed, adjustability of the latch becomes necessary to regulate the sensitiveness of operation.

Undoubtedly, by considering the foregoing 30 description in association with the drawings, persons familiar with devices of this class will be able to obtain a clear understanding of the same. For this reason, a more lengthy description is thought unnecessary.

Minor changes coming within the field of 35 invention claimed may be resorted to if desired.

Having thus described the invention, what 40 we claim as new and desire to secure by Letters Patent is:—

1. A loom attachment of the class de-

scribed comprising a base plate having a transversely elongated guide at one end, an arched bracket at the opposite end, a pivot member mounted for swinging movement in said arched bracket, a longitudinally and laterally movable feeler arm having one end portion extending through said guide and having the opposite end portion connected 45 with said pivot member, an adjustable contact member screw carried by said base plate, a cooperating contact carried by the intermediate portion of the feeler arm, spring means associated with said feeler arm, 50 together with a spring pressed pivotally mounted latch cooperable with the intermediate portion of the feeler arm, said latch being adjustably mounted on the base plate.

2. In a loom attachment of the class described, a base plate provided with a transversely elongated guide at one end, an arched bracket at the opposite end, a pivot member mounted for swinging movement in said arched bracket, a longitudinally and laterally movable feeler arm having one end portion extending through said guide and having the opposite end portion connected 60 with said pivot member, said feeler arm embodying a comparatively wide central portion 65 provided with a bevelled shoulder, spring means associated with said feeler arm, an adjustable contact screw mounted on said base plate, a cross piece carried by said feeler arm and cooperable with said screw, an adjustably mounted spring pressed latch mounted on said base plate, said latch 70 having a depending detent cooperable with said feeler arm for maintaining said cross piece in engagement with said contact screw. 75

In testimony whereof we affix our signatures.

RANSFORD O. CANEDY.
JAMES M. CANEDY.
